(57) **CLAIM**

The ornamental design for a bottle as shown and described.

DESCRIPTION

1. Bottle

3. Bottle

Fig. 1.1 is a perspective view of an embodiment of the bottle, showing my design.

Fig. 1.2 is another perspective view thereof.

Fig. 1.3 is yet another perspective view thereof.

Fig. 1.4 is a bottom view thereof.

Fig. 1.5 is a right-side view thereof.

Fig. 1.6 is a left-side view thereof.

Fig. 3.1 is a perspective view of another embodiment of the bottle, showing my design.

Fig. 3.2 is another perspective view thereof.

Fig. 3.3 is yet another perspective view thereof.

Fig. 3.4 is a bottom view thereof.

Fig. 3.5 is a right-side view thereof.

Fig. 3.6 is a left-side view thereof.

The lower opacity areas in the drawings depict portions of the bottle that form no part of the claimed design.

1 Claim, 12 Drawing Sheets
